US0D1014979S

(12) **United States Design Patent** (10) Patent No.: **US D1,014,979 S**
(45) Date of Patent: ** Feb. 20, 2024

(54) **COMBINED DISPENSING BRUSH AND HOLDER FOR FABRIC CARE APPLIANCE**

(71) Applicant: **WHIRLPOOL CORPORATION**,
Benton Harbor, MI (US)

(72) Inventors: **Seth E. Bixby**, Stevensville, MI (US);
Marcus A. Cannon, St. Joseph, MI (US); **Sayer J. Murphy**, St. Joseph, MI (US); **Jun Young Park**, St. Joseph, MI (US); **Joel R. Shinaberry**, St. Joseph, MI (US)

(73) Assignee: **WHIRLPOOL CORPORATION**,
Benton Harbor, MI (US)

(**) Term: **15 Years**

(21) Appl. No.: **29/860,064**

(22) Filed: **Nov. 16, 2022**

(57) **CLAIM**

The ornamental design for a combined dispensing brush and holder for fabric care appliance, as shown and described.

DESCRIPTION

FIG. 1 is a perspective view of a combined dispensing brush and holder for fabric care appliance according to the design; FIG. 2 is a front elevation view thereof; FIG. 3 is a back elevation view thereof; FIG. 4 is a right side elevation view thereof; FIG. 5 is a left side elevation view thereof; and, FIG. 6 is a top plan view thereof, wherein a bottom plan view thereof shows no part of the claimed design. The portions of the article shown in evenly-spaced broken line form no part of the claimed design. Dash-dot-dash broken lines represent the bounds of the claimed subject matter and also form no part of the claimed design.

1 Claim, 6 Drawing Sheets
